United States Patent

Des. 242,192
Patented Nov. 9, 1976

242,192

COMBINED STOOL AND TRAY UNIT

Bobby J. Robinson, 129 Meadow Drive,
Converse, Tex. 78109

Filed Feb. 13, 1974, Ser. No. 442,163

Term of patent 14 years

Int. Cl. D6—01

U.S. Cl. D6—40

Published under the Second Trial Voluntary Protest
Program on Mar. 16, 1976, as document No. B442,163

FIG. 1

FIG. 3

FIG. 2

FIG. 4

FIG. 1 is a perspective view of my invention with the tray in the innermost position.

FIG. 2 is a perspective view of my invention taken from the opposing sides as shown in FIG. 1 with the tray in the outermost position so that the ash tray and coaster are available.

FIG. 3 is a side view of my invention with the tray in the innermost position.

FIG. 4 is a bottom view of my invention with the tray in the innermost position.

I claim:

The ornamental design for a combined stool and tray unit, as shown.
